UNITED STATES PATENT OFFICE.

FRITZ SAUTER, OF BASEL, SWITZERLAND.

MOTOR-DRIVEN QUICK-ACTION ELECTRIC SWITCH.

1,378,283.

Specification of Letters Patent. Patented May 17, 1921.

Application filed December 10, 1919. Serial No. 343,897.

To all whom it may concern:

Be it known that I, FRITZ SAUTER, a citizen of the Swiss Republic, and resident of Basel, Switzerland, have invented new and 5 useful Improvements in Motor-Driven Quick-Action Electric Switches, of which the following is a full, clear, and exact specification.

The invention relates to motor driven electric switches with quick-action rotary movement in which an electric motor is arranged to drive by means of its shaft a gearing designed to periodically release a snap-action device connected to the rotary switch shaft.

15 In such switches there is possibility of the switch contacts becoming seized or jammed so that the released snap-action device fails to operate and quick-action switching ceases. In order to cause positive actuation of the 20 switch in such cases the present invention proposes to introduce a normally inoperative "follower" coupling between the driving gear and the switch shaft, this coupling coming into operation in the event of failure 25 of the snap-action device in such a manner as to cause a positively actuated rotating connection of the driving gear to the switch shaft.

The accompanying drawing illustrates a 30 constructional form of the improved motor mechanism. Figure 1 is a front view, partly a vertical section thereof; Fig. 2 is a transverse section on line A—B of Fig. 1.

Referring to the drawing a small electric 35 motor *b* is arranged to drive by means of its shaft *a* a self-stop worm drive *c*, *d* whereby motion is transmitted to a train of gearing *f*, *g* which is arranged to periodically release a snap-action device connected to the 40 rotary switch shaft *h*. The snap-action device comprises a spring barrel *i*, secured to the shaft *h* as indicated at *h*¹, the spring barrel containing a drive spring *j* the inner end of which as indicated at *j*¹ is secured to the 45 shaft *g*¹ of the gear wheel *g*, the spring *j* being arranged to be gradually wound up by the movement of the driving mechanism. The snap-action device also comprises a radially arranged check-arm *n* mounted 50 upon an eccentric *m* secured to the shaft *g*¹, this check-arm projecting through an opening *o* in the side of the spring barrel and

normally abutting against one or other of a number of stops *p* mounted on the spring barrel (see Fig. 1).

During the gradual rotation of the eccentric *m* due to its being driven by the gear wheel *g* the check-arm *n* is gradually moved inward and is finally freed from the stop *p* with which it engages, whereupon the spring *j* which has been wound up during this movement gives up its energy to the spring barrel *i* which is now released and thereby actuates the switch shaft *h* by a quick impulsive motion. The rotary movement thus brought about extends over an angle of approximately 90° and since the check-arm *n* is itself rotated on the eccentric *m* the check-arm again comes into a position in which it is arrested by the next stop *p*.

Mounted on a ring *g*² carried by the driving gear wheel *g* is a pin or rod *s* which is normally permitted free movement in a sufficiently long slot *t* in the spring barrel *i*. This device is out of action so long as the switch is properly operative and serves merely as a safety device. If the release of the spring barrel *i* fails for any reason, so that the contact carrier *u* and its contacts remain stationary, the quick-action switching being interrupted, the operation of the switch by means of the gear wheel *g* is continued by reason of the pin *s* moving to the far end of its slot *t* with which it engages and carrying along with it the spring barrel *i*. This in turn causes positive rotary operation of the switch shaft *h* so that the latter then continues to be actuated in a positive manner.

It will be understood that the worm and wheel drive of the mechanism may be replaced by a gear wheel or friction drive mechanism or in general by any other form of transmission.

What I claim is:

In a motor driven electric switch, the combination of an electric motor, a drive gearing connected thereto, a rotary switch shaft, a spring barrel connected with the latter, a radially movable check-arm, a rotary eccentric for the operation thereof, said barrel being provided with a side opening for said check-arm, a stop for the latter, and a coupling pin carried by said driving gearing,

said barrel being provided with a long slot and said coupling pin being arranged within this slot so as to be inoperative during normal working and to only become operative if the spring barrel should be unable to rotate the switch shaft, substantially as described.

In witness whereof I have hereunto signed my name this 13th day of November, 1919, in the presence of two subscribing witnesses. 10

FRITZ SAUTER.
